UNITED STATES PATENT OFFICE.

FRED P. LOVEJOY, OF SPRINGFIELD, VERMONT.

METAL-WORKING TOOL.

1,242,708.

Specification of Letters Patent.

Patented Oct. 9, 1917.

Application filed May 24, 1917. Serial No. 170,652.

To all whom it may concern:

Be it known that I, FRED P. LOVEJOY, a citizen of the United States, residing at Springfield, in the county of Windsor and 5 State of Vermont, have invented new and useful Improvements in Metal-Working Tools, of which the following is a specification.

This invention relates to metal-working tools and its object is to provide an improved combination consisting of a cutter, a holder therefor, and means for securing the cutter rigidly in the holder, to the end that the cutter and holder will be, to all intents 10 and purposes, as rigid as though they were integral. The advantage of such a combination is that a cutter of the highest grade and most expensive steel may be used economically with a holder of less expensive 15 steel, and that when the cutter has become too far worn by use and by resharpening it can be thrown away and another cutter substituted for it without excess waste.

The cutter is locked in the holder by a 20 shoe, and is tightened by a cotter that is arranged to exercise a wedging action upon the shoe. The cutter and shoe are provided with interlocking teeth that sustain the end-thrust of the cutter and that afford various 25 positions of adjustment of the cutter. Inasmuch as the wedging action occurs between the cotter and the shoe it does not wear or otherwise injure the interlocking teeth of the shoe or those of the cutter, and an exceedingly 30 tight wedging action may be produced without liability of injuring the teeth.

Referring to the accompanying drawings, which illustrate the present invention in what I now consider the preferred form:

40 Figure 1 represents a side elevation of a complete tool the several parts of which are assembled for operation.

Fig. 2 represents a section through the structure intersected by line 2—2 of Fig. 1.

45 Fig. 3 represents a section in a vertical plane of the portion of the holder in which the sockets are formed.

Fig. 4 represents a side elevation of the wedging cotter.

50 Fig. 5 represents a cross-section through the locking shoe.

The same reference characters indicate the same parts wherever they occur.

The holder 10 is provided with three sockets 55 11, 12, and 13 respectively, the first for a cutter 14, the second for a locking shoe 15,

and the third for a cotter 16. These sockets are all preferably cylindric in form, and the members 14, 15, and 16 are made from cylindric stock. The sockets 11 and 13 are 60 nearly parallel but their axes, as indicated by Fig. 3, are at a slight angle relatively to each other, although it would be within the scope of the invention, to some extent at least, to arrange them strictly in parallel 65 relation. The socket 12 intersects both the sockets 11 and 13 and is arranged to extend substantially at right angles in relation to them.

The cutter 14 is provided with a series of 70 teeth 17 whereby it may be locked against endwise movement. The locking shoe 15 is provided with locking teeth 18 adapted to occupy interlocked relation with the teeth 17. The teeth 17 extend substantially at 75 right angles to the axis of the cutter, but the teeth 18 extend substantially parallel to the axis of the shoe, and when the shoe and cutter are interlocked with each other in their respective sockets the teeth serve to sustain 80 end-thrust of the cutter, and such end-thrust is transmitted by the shoe to that portion of the holder indicated at 19 in Fig. 3.

The shoe is provided with a notch diametrically opposite the teeth 18, to receive a 85 portion of the cotter 16 as shown by Fig. 2, the shoe being thereby locked so that it cannot slip from its socket. The shoe and cotter are provided with flat faces 20 and 21 respectively, which faces are adapted to bear 90 one upon the other, face 21 being inclined slightly in relation to the axis of the cotter to compensate for the angular relation of the axes of sockets 11 and 13. Thus, although the cotter has a wedge formation, 95 when the several parts are assembled in co-operative relation as shown by Fig. 1, the face 21 is substantially parallel to the axis of the cutter. For this reason the flat face 20 of the locking shoe may be parallel to the 100 plane of the teeth 18, and the shoe may be reversed, end for end, without affecting its co-operative relation to the cutter or its co-operative relation to the cotter.

The cotter nevertheless exercises a wedging action upon 105 the shoe, when driven endwise from the top of the holder toward the bottom, said action being due to the angular relation of the sockets 11 and 13. This relation of the sockets 11 and 13 is utilized to cause an automatic tightening effect in consequence of 110 end-thrust of the cutter. The diameter of

socket 12 is slightly greater than the diameter of the locking shoe, to permit such lateral movement of the shoe as may be necessary to take up clearance between it and the cutter and clearance between the cutter and the wall of socket 11 diametrically opposite the shoe.

When the cotter is being driven to tighten the cutter its frictional action on the shoe moves the latter against portion 19 (Fig. 3) of the holder, and at the same time the wedging action of the cotter moves the shoe laterally toward the cutter to tighten the latter as hereinbefore explained. Thus all slack or clearance between the cutter and the portion 19 of the holder is taken up by the operation of driving the cotter, so that there will be no endwise slipping of the cutter, or "chattering" when the cutter is operating.

I claim:

1. A metal-working tool comprising a cutter, a locking shoe, a cotter, and a holder having sockets for said parts, the cutter and the cotter being arranged in approximate parallelism with the shoe interposed transversely between them, the shoe and the cutter having interlocking teeth arranged to sustain end thrust against the cutter.
2. A metal-working tool comprising a cutter, a holder therefor, said holder having a socket for said cutter, a locking shoe, said holder having a socket for said shoe extending substantially at right angles to the cutter-socket, said cutter and shoe having interlocking teeth arranged to sustain end-thrust of the cutter, and a cotter, said holder having a cotter-socket extending substantially at right angles to said shoe-socket, said cotter being arranged to move said shoe laterally in the direction of end-thrust of the cutter, said cotter being arranged to exercise a wedging action on said shoe to tighten the latter and the cutter.
3. A metal-working tool comprising a cutter, a transversely arranged locking shoe, a cotter, and a holder having sockets for said cutter, said shoe and said cotter, said shoe and said cutter having interlocking teeth arranged to lock the cutter against endwise movement, said shoe having a notch to receive said cotter, said cotter being longitudinal of the cutter and arranged to lock said shoe in the holder, and being arranged in the notch to exercise a wedging action on the shoe to interlock the shoe with the cutter.
4. A metal-working tool comprising a cutter, a holder therefor, a locking shoe, said holder having sockets for said cutter and said shoe respectively, said cutter and said shoe having interlocking teeth arranged to

sustain end-thrust of the cutter, said shoe having a flat face substantially opposite said teeth, and a cotter having a flat face 65 arranged to bear on said flat face of the shoe, said holder having a socket for said cotter, said cotter being arranged to exercise a wedging action on said flat face of the shoe to tighten the shoe and said cutter. 70

5. A metal-working tool comprising a cutter having a series of teeth arranged to sustain end-thrust of the cutter, a holder having a socket for said cutter, a locking shoe, said holder having a socket for said shoe, 75 said shoe being movable transversely of said cutter and having teeth arranged to slide between said teeth of the cutter to lock the cutter against endwise movement, and a cotter having a flat face arranged at a slight 80 incline relatively to its axis, said holder having a socket for said cotter, said cotter being arranged to exercise a wedging action on said shoe to tighten the latter and the cutter, said shoe having a flat face arranged 85 to coact with said flat face of the cotter, said flat faces being substantially parallel to the axis of said cutter.

6. A metal-working tool comprising a cutter having a series of teeth arranged to sustain end-thrust of the cutter, a holder having a socket for said cutter, a locking shoe, 90 said holder having a socket for said shoe, said shoe being movable transversely of said cutter and having teeth arranged to slide 95 between said teeth of the cutter to lock the cutter against endwise movement and a cotter, said holder having a socket for said cotter, said cutter-socket and said cotter-socket being arranged to cause the cutter 100 and cotter to converge relatively to each other when they are moved in the direction of end-thrust of the cutter.

7. A metal-working tool comprising a cutter having a series of teeth arranged to sustain end-thrust of the cutter, a holder having a socket for said cutter, a locking shoe, 105 said holder having a socket for said shoe, said shoe being movable transversely of said cutter and having teeth arranged to slide 110 between said teeth of the cutter to lock the cutter against endwise movement, and a cylindric cotter having a flat face arranged to slide on said shoe, said holder having a cylindric socket for said cotter, the axis of 115 said cotter-socket being inclined relatively to the axis of said cutter-socket to cause a wedging action of said cotter upon the shoe in consequence of endwise movement of the cotter.

In testimony whereof I have affixed my signature.

FRED P. LOVEJOY.
